UNITED STATES PATENT OFFICE.

JAMES A. STEWART, OF HOLLIDAYS COVE, WEST VIRGINIA.

DRIVE MECHANISM FOR AIRSHIPS.

1,288,258.

Specification of Letters Patent. Patented Dec. 17, 1918.

Application filed March 20, 1918. Serial No. 223,616.

To all whom it may concern:

Be it known that I, JAMES A. STEWART, a citizen of the United States, residing at Hollidays Cove, in the State of West Virginia, have invented new and useful Improvements in Drive Mechanism for Airships, of which the following is a specification.

This invention relates to drive mechanism for airships, aeroplanes or the like and has for its primary object to provide drive mechanism that is capable of either giving direct vertical movements to the airship or horizontal movements.

An object of the invention is to provide mechanism capable of instantly moving an airship vertically and so constructed as to assume an inoperative position when other mechanism is thrown into operation for giving horizontal movements to the airship.

Besides the above my invention is distinguished by pairs of propellers acting in conjunction, one operating when the engine is in low speed, the other operating when the engine is in high speed, and first mentioned propeller thrown into inoperative position.

With these and other objects in view the invention will be better understood from the following detailed description taken in connection with the accompanying drawing wherein;

Figure 1 is a rear elevation of the mechanism showing parts in section.

Fig. 2 is an enlarged sectional view showing a portion of the lifting propeller.

Fig. 3 is a detailed view of the flexible joint.

Again referring to the drawing the numeral 1 designates a base in which is rotatably mounted a casing 2 which may consist of a plurality of sections. The casing in this particular instance is of a U shaped formation and rotatably mounted therein is a drive shaft 3 consisting of vertical sections 4 and 5 connected to a horizontal section 6 by flexible joints in the form of coil springs 7. The section 6 is directly connected to the drive gear 8. From this arrangement it will be seen that the sections 4 and 5 may extend in a vertical direction as shown in the drawing or may assume a horizontal position by rotating the casing within the base 1. It is of course to be understood that any suitable device may be used for turning the casing in the base.

It will be noted by referring to Fig. 1 that

I use two sets of propeller mechanism and as they are identical in construction the following description will be limited to that mechanism shown at the left of the drawing. 60

The protruding end of the section 4 has fixed thereto a cone-shaped hub 9 that supports the propeller blades 10 of a drive propeller 11. Slidably mounted on the casing 2 is a tube 12 terminating in a cone-shaped 65 hub 13 adapted to slide into engagement with the hub 9 so that the tube and section 4 may rotate as a unit. The blades 14 of the lifting propeller 15 have a knife joint 16 with the hub 13 so that the blades may be 70 moved toward an operative or an inoperative position and when in an operative position rigidly held against independent movements. Slidably mounted on the tube 12 is a collar 17 connected to the blades by links 75 18. Sliding movements may be given to the collar 17 in any suitable manner such as by the pivoted lever 19 having a forked extremity 20 engaging a groove 21 in the collar. This lever 19 may be operated in any suitable manner such as by a flexible cable 22 passing around suitably arranged pulleys so that the lever may be operated from a remote point. 80

From the foregoing description taken in 85 connection with the accompanying drawing it will be seen that when it is necessary to lift the airship vertically the lever 19 may be operated for extending the blades 14 to an operative position. When this takes place further movement of the lever 19 will force the hub 13 into engagement with the hub 9 for rotating the tube 12 with the shaft section 4. Before this takes place the engine driving the gear 8 will be thrown into low speed as the pitch of the blades 14 are of a degree to give great lifting power at a relatively small number of revolutions of the propeller. Thus it will be seen that the action of the propeller 11 when rotated will 95 be reduced. When it is found necessary to drive the airship forward the casing 2 will be rotated in the base for throwing the shaft sections 4 into a horizontal position. When this takes place the propellers 15 will be 100 105 collapsed.

It is to be understood that the structural embodiment of the invention as a whole and its various features as shown is merely illustrative and not restrictive, since I am well 110 aware that many of the details of construction can be widely varied without depart-

2
ing from the spirit of the invention, I therefore do not desire to be limited in these particulars or in any others, except as set forth in the appended claims.

5 Having described my invention, what I claim is;

1. Drive mechanism for airships comprising a rotatably mounted casing a drive shaft mounted therein and having its ends projecting beyond said casing, propellers fixed thereto and collapsible propellers adjustably mounted to engage said first mentioned propeller.

10 2. Drive mechanism for airships comprising a rotatably mounted casing a drive shaft mounted therein and having its ends projecting beyond said casing, propellers fixed thereto and collapsible propellers adjustably mounted to engage said first mentioned propeller.

15 20

3. Drive mechanism for airships comprising in combination a drive shaft a casing supporting the shaft a propeller fixed to said shaft a second propeller consisting of a hub and blades pivotally connected to the hub and means for extending said blades to an operative position and moving the hub into engagement with the first mentioned propeller.

30 4. Drive mechanism for airships comprising a casing a drive shaft supported thereby a propeller having a cone-shaped hub fixed to said shaft a second propeller consisting of a hub adapted to detachably engage the hub of said first propeller and having pivotally mounted blades, a slidably mounted collar having a link connection with the blades and a device for giving movements to the collar.

35 In testimony whereof I affix my signature.
JAMES A. STEWART.
